UNITED STATES PATENT OFFICE.

JOSEF PAUL, OF DRESDEN-STRIESEN, GERMANY, ASSIGNOR TO FEINMASCHI-NENBAU G. CALBERLA, G. M. B. H., OF DRESDEN, SAXONY, GERMANY.

DEVICE FOR FEEDING TOBACCO IN CIGARETTE-MACHINES.

SPECIFICATION forming part of Letters Patent No. 709,507, dated September 23, 1902.

Application filed August 24, 1901. Serial No. 73,189. (No model.)

To all whom it may concern:

Be it known that I, JOSEF PAUL, a subject of the King of Saxony, residing at Dresden-Striesen, in the Kingdom of Saxony, German Empire, have invented certain new and useful Improvements in Devices for Feeding Tobacco in Cigarette-Machines, of which the following is a full, clear, and exact description.

10 My present invention relates to improvements in devices for feeding tobacco in cigarette-machines, and the advantage of my improvements over existing devices of the kind is that the rollers by which the tobacco 15 is transported and simultaneously loosened are driven at a uniform velocity, while the small rollers by which the tobacco is removed from the transport-rollers are so constructed and arranged as to thoroughly mix the tobacco.

In the accompanying drawings are shown two ways of carrying out my invention, both in section.

Referring to Figure 1, at the lower end of the 25 hopper *a* are arranged two rollers *b*, provided on their peripheries with a number of teeth inclined in opposite directions. These rollers are rotated in contrary directions, as shown by the arrows. The tobacco thrown into the 30 hopper *a* is conveyed right and left around the outer halves of the rollers *b*, from which it is removed by the small rollers *d*. These rollers *d* likewise are provided with teeth and rotated in opposite directions, so that the 35 tobacco will be thrown together and then pass in a thoroughly mixed condition through the outlet *e* into the shaping-wheel *f*. In order to prevent too much tobacco from being drawn around the rollers *b* and a consequent 40 stopping of the machine, are provided rollers *g*, which are arranged above and quite or approximately in contact with the teeth of the roller *b* and are rotated at a high velocity in the direction of the arrows.

In Fig. 2 the construction is somewhat simpler. As in Fig. 1, there are two rollers *b'*, which rotate in opposite directions, and underneath these rollers are likewise provided smaller toothed rollers *d'*. The tobacco thrown into the hopper *a* passes between the large rollers *b'* and is removed by the oppositely-rotating rollers *d'*, passing then through the outlet to the shaping-wheel. As the tobacco is thrown by the rollers *d'* against the sides of the hopper it is loosened as much as possible. To prevent too much tobacco from passing between the rollers *b'*, a triangular knife is arranged between the rollers at the top, by which the excess quantity is cut off. A similar knife *l* is arranged between the rollers at the bottom and serves the same purpose.

What I claim, and desire to secure by Letters Patent of the United States, is—

1. A tobacco-feed device for cigarette-making machines, comprising in combination a hopper, two oppositely-rotating toothed rollers at the lower end of said hopper which rotate at the same speed, and two smaller toothed rollers adapted to remove the tobacco from the first rollers and thoroughly mix the same, substantially as set forth.

2. A tobacco-feed device for cigarette-making machines, comprising in combination, a hopper, two oppositely-rotating toothed rollers at the lower end of said hopper which rotate at the same speed, two smaller toothed rollers adapted to remove the tobacco from the first rollers and thoroughly mix the same, and rollers, one in contact with each of the first-named rollers and adapted by quickly rotating to prevent the passage of too much tobacco, substantially as set forth.

In witness whereof I hereunto subscribe my signature in presence of two witnesses.

JOSEF PAUL.
